UNITED STATES PATENT OFFICE.

ANTON MILOŠ, OF NEW YORK, N. Y.

LIFE-PRESERVER.

1,152,199.

Specification of Letters Patent. Patented Aug. 31, 1915.

Application filed June 4, 1915. Serial No. 32,056.

To all whom it may concern:

Be it known that I, ANTON MILOŠ, a subject of the Emperor of Austria-Hungary, residing at New York, in the county of New York and State of New York, have invented 5 certain new and useful Improvements in Life-Preservers, of which the following is a specification.

The present invention relates to improvements in life preservers, the main object of 10 which is to construct a life preserver on the principle of turtle shells, so that the wearer can at will withdraw into the shell or project his legs and arms outwardly therefrom 15 when he desires to propel himself.

With this object in view my invention consists of a buoyant box-shaped receptacle having outwardly projecting flexible and waterproof leg and arm receiving pockets 20 and a pocket for storing away things and also means for securing the device to his body. The box proper, which, when the wearer has his legs and arms projected into the pockets is adapted to envelop his trunk 25 and head, serves as a receptacle for storing away things, to contain a water reservoir, etc., and as a stateroom into which the user may retire to occupy a sitting position during a quiet sea.

30 My invention also consists in the construction, combination and arrangement of parts, which will be hereinafter fully specified and set forth in the appended claims.

Referring to the accompanying drawing, 35 which forms part of this specification and in which similar reference letters denote corresponding parts, Figure 1 shows a side elevation of my device, as applied to the body of the user in standing position; Fig. 2 is a plan view thereof; Fig. 3 is a vertical section of the device shown as floating on the water and Fig. 4 is an enlarged sectional detail.

45 My device substantially consists of a buoyant body comprising a box-shaped waterproof receptacle *a* of rigid material, which with respect to Fig. 1, at its rear and bottom is cut out, as at *a'*, *a''*. Fastened to the box around the edges of the cut out 50 parts is a flexible piece *b* of waterproof material formed at one end with outwardly projecting leg receiving pockets *c* in form of pantaloons, and at the opposite end with similar pockets *d* for receiving the arms of 55 the wearer. The central portion *e* is in the form of a bag or sack and serves as a con-

tainer of articles, such as food or the like or other load adapted to counterbalance the load on the back of the wearer when in standing position. On the opposite side or 60 back of the rigid box is an opening *a³* through which the user can enter the box. Around the opening *a³* projecting flanges *a⁴* are provided and, hinged at one side of the opening, as at *a⁵* is a lid *f*, which can be 65 closed and opened at will. A suitable locking device, such as a spring *f'*, may be provided to hold the lid tightly closed when so desired.

At the upper or forward end the box is 70 formed with a compartment *g* serving as a reservoir to contain drinking water for the user. At the opposite end a pocket *h* is provided to receive the belongings of the user. In the front or lower wall the box is 75 provided with a glass window *i*, through which the user after applying the device is enabled to see his way while walking or propelling himself in the water. An air supply pipe *k* may be provided on the back or upper side 80 of the box which may be arranged and constructed in a suitable manner to prevent water from entering the box through the same. To allow of the occupant or his device being easily fished out of the water, a 85 number of wires *l* or the like may be provided, preferably as shown.

It will be seen that by virtue of the above 90 named construction, the user on entering the box and slipping his arms and legs into the respective pockets will have his body and head entirely concealed within the box and can in an upright position freely propel himself on land, in shallow water or on board of ship. In water the user may adopt 95 a horizontal swimming position and propel himself by manipulating his arms and legs. During a quiet sea, the user may withdraw his arms and legs from within the respective 100 pockets and on opening the lid may project his head through the opening *a³*. He may sit down on the rigid part *a⁶* of the box and place his legs in the pocket *e* or he may hook a seat *m* to the edges *a⁴* around the 105 opening *a³*. To secure the device to the body of the user, straps *n* like suspenders or the like may be attached in the box which the user can readily slip over his shoulders, as shown in Fig. 1.

110 While I have referred to one form of construction of my device, it will be understood that various modifications may be

made by those skilled in the art without departing from the spirit of my invention and I, therefore, do not wish to restrict myself to the details shown and described.

5 What I claim and desire to secure by Letters Patent is:

1. A life preserver, consisting of a rigid receptacle, having at one side an entrance opening, and at the opposite a window and 10 cut out parts and a piece of flexible material covering said cut out parts and formed with leg and arm receiving members.

2. A life preserver, consisting of a rigid receptacle, having at one side an entrance opening and a lid therefor, and at the opposite side a piece of flexible material in form 15 of a bag and provided with extensions forming leg and arm receiving pockets.

3. A life preserver, consisting of a rigid 20 box, having flexible extensions forming leg and arm receiving pockets and a flexible bag to receive some load which will coun-

terbalance the weight of the box when the user is in standing position.

4. A life preserver, consisting of a rigid 25 receptacle having at one side an entrance opening and at the opposite side a piece of flexible material formed with arm and leg extensions and means on the receptacle for catching and fishing the latter out of the 30 water.

5. A life preserver, consisting of a rigid receptacle having at one side an entrance opening, a lid therefor, and on the opposite 35 side a piece of flexible material formed with arm and leg extensions and an air supply pipe on said receptacle.

In testimony whereof I affix my signature in presence of two witnesses.

ANTON MILOŠ.
